WEB SUPPLY MEANS

David J. Scott, Plainfield, N. J.

Application November 22, 1932, Serial No. 643,847

26 Claims. (Cl. 242—58)

This invention relates generally to web supply means, and has more particularly reference to roll change mechanism such as are used in connection with printing or other web-pulling machines.

The main object and feature of the invention is to provide simple and effective means whereby a replenishing web roll can be substituted for an active web roll without the necessity of stopping the printing machine, or without slowing it down unduly, in such a way as to avoid undue stress on the running web when effecting a roll change. Other features of invention will appear as the specification proceeds.

In the accompanying drawings, the invention is disclosed in a concrete and preferred form in which:

Fig. 1 is an end elevation view, partly in section of a device embodying the invention;

Fig. 2 is a sectional view substantially on the plane of line 2—2 of Fig. 1, with parts broken away and in section;

Fig. 3 is an enlarged view of one of the arms of the spider or reel with its equipment;

Fig. 4 is a sectional view substantially on the plane of line 4—4 of Fig. 3;

Fig. 5 is a view looking in the direction of arrow 5 of Fig. 3;

Fig. 6 is a diagrammatic view showing the movement of the replenishing roll when a pasted joint is to be made; and

Fig. 7 is a diagrammatic view of the electrical controlling means of the device.

A plurality of rotatable web rolls, here three in number, are employed, said rolls being indicated by 20, 21 and 22. 20 is the active roll and has its running web 23 threaded into a printing or other machine 24 that unwinds the web from the roll. 21 and 22 are replenishing web rolls awaiting to be employed and which in turn become active rolls. The three rolls are carried by spaced-apart arms 25 of a spider or reel 26, the center of rotation of which is indicated by shaft 27 and, when a roll change is to be effected, shaft 27 is turned clockwise in Fig. 1 to bring the periphery of replenishing roll 21 in contact with running web 23 so as to unite the webs of the active and replenishing rolls by means of a pasted joint in a manner well understood. Any suitable means can be employed to turn shaft 27 but, as here shown, an electric motor 28 is used for this purpose, said motor driving said shaft by a train of transmission elements 29 to gear 36. Arms 25 of the spider carry bearings 37 for the reception of rotatable core-engaging

or web roll supporting means 38 that are provided with brake drums 39 for the reception of brake shoes 40, said brake drums having non-radial cooling fins 41 that by rotation of the brake drums, during the unwinding operation, tend to cool the braking elements. Each brake shoe is actuated by a brake lever 42 pivotally connected to one brake shoe member at 43 and pivotally connected to the other brake shoe member by a link 44. Although each web roll supporting means is equipped with a brake mechanism, it is only desired to control the brake mechanism of the active web roll. In order to accomplish this, the following means are employed: a plurality of rockshafts 45 are supported by shaft 27. On each rockshaft is an actuating lever 47 carrying a roller 48 to engage its corresponding brake lever. Also mounted on said rockshafts are a plurality of arms 49, one on each rockshaft and each carrying a roller 50. 20 51 indicates a cam to engage each roller 50 as the latter passes beneath the same, and said cam is pivotally carried by two levers 52 that are mounted on pins 53 supported on the framework. Levers 52 are connected by link 55 and one of 25 said levers is further pivotally connected to controller arm 56 which latter in turn is connected to controller roller 57 pivotally supported on shaft 58 which carries a balancing weight 59 and has connection with the plunger of a dashpot in accordance with the well-known Jones tension construction. Web 23 is carried over rollers 61 and 62 and around roller 57, and said roller 57 moves back and forth in response to the tightness or slackness of the web. Thus if 35 the active web roll is rotating too fast in response to the pull of the printing machine, slack will accumulate in the web and said roller 57 will move to the right in Fig. 1 thereby exerting an upward pull on rod 56 which has the effect of 40 bringing cam 51 nearer the center of shaft 27, thereby depressing roller 50 and actuating brake lever 42 to make the brake of the web roll more effective. Conversely, if the active web roll is rotating too slowly in response to the pull of 45 the printing machine, web 23 will move roller 57 to the left in Fig. 1, and this will, through the connections previously described, render the brake of the active web roll less effective. It will be seen that when replenishing roll 21 is 50 brought into contact with web 23 to make a pasted joint, it is necessary to provide a backing means for the running web. As here shown, this backing means consists of a set of tapes or aprons 63 carried by a frame 64 pivotally sup- 55

ported at 65 on the main frame of the machine and having sustaining means 65a that admit of a limited pivotal movement of said frame but which normally hold the tapes out of contact with the running web. One end of the tapes may also be mounted in a spring-pressed bearing 66 that permits the tapes to more readily conform to the contour of the replenishing roll when the latter brings the running web against the tapes.

Continued rotation of shaft 27 causes the replenishing roll to pass by the tapes to the final position occupied by roll 29 in Fig. 1. In the present instance, tapes 63 are not driven. Carried by one of the arms 25, of each set of arms that support a roll, is a boosting motor 69 the armature pinion 70 of which engages a gear 71 of the core-engaging means. This motor, 69, is energized only about the time when its roll is a replenishing roll that acts to effect a pasted joint between its web and the running web, and the object of the motor is to relieve undue strain on the running web. Two methods may be employed to energize motor 69, one of which consists in partially closing a circuit by rotation of the reel but not to complete the circuit until an initial rotation has been given to the replenishing roll, such initial rotation of the replenishing roll being effected by a push of the hand of the operator, or by a slight rotating movement of the roll caused by its engagement with the running web and by the impingement of the latter against the backing member. The other method consists in relying wholly upon rotation of the reel to close the circuit. To this end there are arranged certain stationary and rotating contacts, and, preferably, the rotating contacts are in the form of rings or sectors 72 and 73 carried by gear 36 and the stationary contacts or brushes 74 and 75 are carried by bracket 76 of the framework. As shown in Fig. 6, replenishing roll 21, and its sector 73, is shown in dotted lines at the beginning of the rotating movement of the reel, and the parts are shown in full lines at the point where the replenishing roll has deflected the running web into contact with the backing member. Sector 72 may, of course, be a continuous ring. As previously indicated under the first-mentioned method, when the replenishing roll occupies the full-line position of Fig. 6, the circuit through motor 69 is partially closed and, by engagement of the roll, the running web and the backing member, said roll is given a slight rotation about its own axis sufficient to bring dog 78 (Fig. 3), carried by gear 71, into engagement with switch 79, stationary on the framework thereby completing the circuit. This energizes the boosting motor and causes it to drive the replenishing roll through the core-engaging means of the latter. After about one-half revolution, dog 80, also carried by gear 71 turns switch 79 and ruptures the circuit through motor 69. Dogs 78 and 80 are spring-pressed as shown in such a manner that during the subsequent rotation of the roll its speed will be sufficient to throw said dogs outwardly by centrifugal action. Also, it will be understood, when the replenishing roll reaches the limit of its movement, due to rotation of the reel, and has become an active roll, brush 75 will no longer be in engagement with sector 73, so that the motor circuit will likewise be broken at that point. In the second-mentioned method above referred to, switch 79 and dogs 78 and 80 will be omitted and the timing of contacts 72, 73, 74 and 75 will be slightly altered. Pinion 70 (Fig. 4) of motor 69

is arranged like the self-starter of an automobile, that is, rotation of motor 69 causes screw 81 to feed said pinion to the left until it meshes with gear 71 and comes against abutment member 82, when it begins to drive 71. When motor 69 ceases rotation, the continued rotation of 5 gear 71 feeds the pinion back to the right until it disengages gear 71. After the pasted joint between the two webs has been effected, the web from the now practically exhausted roll can be 10 severed by hand, but it is preferred to have a web-severing device carried by the spider or reel. Such web-severing device is here indicated by solenoids 77 carried by shaft 27, the detailed construction of which is omitted here but will 15 be found disclosed in detail in my application Ser. No. 642,714, filed Nov. 15, 1932. In order to actuate the web-severing solenoids, however, a third set of contacts or segments 83 is carried by gear 36 and a third brush or shoe 84 is 20 carried by bracket 76. It may be mentioned in passing, that shoes 74, 75 and 84 are carried by an arm 85 that is spring-pressed by means of coiled spring 86, so that when sidewise adjustment of shaft 27 occurs to side register the rolls 25 with the cylinders of the printing machine, said shoes will maintain contact with the complementary rings or sectors.

When the replenishing roll engages the running web and deflects it against the backing 30 member, the tapes of said backing member begin to travel over the pulleys and thus assist in speeding up the web of the replenishing roll. In the case of the first-mentioned method above described, this initial rotation of the replenishing roll closes a circuit through the boosting 35 motor thereby relieving excessive strain on the active web. This in turn enables the running web to assist the replenishing web and thus tends to relieve the load on the boosting motor. Consequently the boosting motor, which has a high 40 ultimate speed, accelerates and increases the speed of the replenishing roll, and so on. In the case of the second-mentioned method, the boosting motor starts to turn the replenishing 45 roll at about the time the pasted joint is made, after which the interaction between the efforts of the motor and the combined efforts of the running web and the backing member occur about 50 in the manner above described.

In addition to assisting in bringing the replenishing web up to speed, the device performs an additional function if the brake control means, previously described, are used. As will be understood, the amplitude of movement of roller 57 is 55 such that it will respond to variations in tension of the running web within relatively narrow limits. Should it now be attempted, by turning the spider on center 27, to bring the periphery of replenishing roll 21 from the dotted line position 60 shown in Fig. 6 into the full line position shown, it will be seen that the running web from active roll 29 will be subjected not only to the retarding influence of its brake but also to the inertia of web roll 21, because the replenishing roll will not 65 merely contact the running web, but will bring said web against the backing means, here tapes 63. This will cause such abnormal fluctuations in the tension of the running web that excessive movement of controller 57 and the brake mechanism 70 will result. This condition is, however, avoided by the interaction between the boosting motor, the running web and the backing member which prevents excessive movement of controller 57 and the brake mechanism. If a motor, as 28, 75

is utilized to turn the spider, it is desirable to employ a limit switch, as indicated in Fig. 7, where a contact 67 controlling the circuit of the motor is shown open, this having been effected by one of the high points of cam 68, carried by shaft 27, at the time the web rolls reach the position indicated in Fig. 1.

A preferred form of electrical equipment is shown in Fig. 7. Motor 28 should be capable not only of turning the spider to effect the bringing together of the two webs, but should also be capable of adjusting the position of the spider in either direction, and said motor is therefore reversible. By closing contact 163, current will flow from line wire 104, over wires 105, 106 and 107, contact 103, wire 108, coil or relay 109 to line wire 110. The energization of coil 109 closes contacts 111 and 112, and current now flows from line wire 104, over wire 113, contact 111, wire 114, motor 28, wires 115 and 116, contact 112, and wire 117 back to line wire 110. This will cause motor 28 to run in a forward direction to turn the spider clockwise in Fig. 1. When contact 118 is closed and 103 is open, current will flow from line wire 104, over wires 105, 106 and 107, contact 118, wire 119, coil or relay 120 and wire 121 back to line wire 110. The energization of coil 120 closes contacts 122 and 123, and current now flows from line wire 104, over wire 124, contact 122, wire 115, motor 28, wire 114, wire 125, contact 123, and wire 126 back to line wire 110. This will cause motor 28 to run in reverse direction to turn the spider counter-clockwise in Fig. 1.

When a roll change is to be effected, the following equipment may be used: contact 127 is closed thereby establishing a circuit from line wire 104, over wires 105 and 128, contact 129, wire 130, contact 67, wire 131, contact 132, wire 133, contact 127, wire 134, coil or magnet 135, and wire 136 back to line wire 110. Energization of coil 135 closes contacts 137, 138 and 139. When contact 137 is closed, it establishes a shunt around contact 127 from wire 133, wire 140, contact 137, wire 141, wire 134, magnet 135, wire 136 and line wire 110, and therefore contact 127 can be released without deenergizing coil or magnet 135. Consequently contacts 137, 138 and 139 will remain closed. When contact 138 is closed current will flow from line wire 104, over wires 105 and 106, contact 138, wire 142, wire 108, magnet 109 and back to line wire 110. It will be seen that this circuit shunts contact 103, but nevertheless energizes magnet 109 to thereby rotate motor 28 in a forward direction as previously described. When contact 139 is closed current will flow from line wire 104, over wires 105 and 144, coil or magnet 146, wire 147, contact 139, and wires 148 and 136 back to line wire 110.

The energization of magnet 146 closes contact 149, and current will now flow from line wire 104, wire 150, contact 149, wire 151, brush 74, ring 72, motor 69, ring 73, brush 75, wire 152, contact 79, wire 152a, contact 129, wire 139, contact 67, wire 131, contact 132, wire 133, wire 140, contact 137, wire 141, wire 134, magnet 135, and wire 136 back to line wire 110. It will be understood that the exact moment when this circuit is closed is determined by the position of ring 73 with respect to shoe 75 and by the closing of switch 79. If switch 79 is omitted, then current passes directly from 152 to 152a over dotted line indication 152b.

When it is desired to energize the web-severing solenoid, contact 143 is closed and current will then flow from line wire 104, wire 150, contact 149, wire 151, brush 74, ring 72, solenoid 77, seg-

ment 83, brush 84, wire 200, contact 143, wire 105 and back to line wire 110 either over the path established by 128 or 144.

Contact 129 is speed-governed being controlled by governor 153 and held closed when said governor is running below a given speed. The governor is driven by shaft 154 and the gearing shown from printing machine 24 so that, in the present case, a roll change cannot be effected unless the printing machine has had its speed reduced to a given point. In order to readily ascertain when such reduced speed has been reached, a lamp or other indicating device as 155 may be employed and it will be seen that this lamp is included in a circuit between contact 129 and line wire 110, said circuit here consisting of wires 156 and 157, which circuit will be established whenever contact 129 is closed, even though contacts 127, 132 and 67 be open, because current can then flow from line wire 104 over wires 105 and 128, contact 129, wire 156, lamp 155, wire 157 and back to line wire 110.

A brief summary of the operation of the device is as follows: when the last previous roll change was effected, limit switch 67 was opened by one of the high points of cam 68 and thus all operating circuits were destroyed and rotation of shaft 27 was stopped, contact 67 remaining open. When it is now desired to make the next roll change, contact 103 is closed just long enough to energize motor 28 to turn shaft 27 sufficiently to bring the high point of cam 68 past contact 67 whereby the latter will close. Contact 127 will now be closed and (contacts 129, 67 and 132 being in their closed position) the circuit previously described will be established through motor 28 to thereby rotate shaft 27 to bring the replenishing roll against the running web so as to deflect the latter against the backing member and in due time energizing the boosting motor. Contact 127 can be released as soon as magnet 135 becomes energized as said magnet will hold the circuit to motor 28 closed in the manner previously described. Contact 143 is now closed thereby actuating the web-severing solenoid while shaft 27 is still rotating. Upon completion of the required movement of shaft 27, contact 67 will be opened by the next high point of cam 68 and the various circuits will be ruptured. Contact 132 is normally closed, but is a stop which can be opened at any time by the operator in case, for any reason, he desires to interrupt the roll change operation.

I claim:

1. Web supply means including: a support having an active web roll the web of which is threaded into a machine that unwinds the web from the roll; a support having core-engaging means for a rotatable replenishing web roll the web of which is to be united to the running web; a backing member normally out of contact with the running web and normally idle but capable of movement by engagement with the running web; means to bring the periphery of the replenishing roll into contact with the running web to thereby deflect the latter into engagement with the backing member so as to effect a pasted joint between the two webs; and additional means, other than the running web and backing member, to rotate the replenishing roll.

2. Web supply means including: a support having an active web roll the web of which is threaded into a machine that unwinds the web from the roll; a support having core-engaging means for a rotatable replenishing web roll the

5 web of which is to be united to the running web; a backing member normally out of contact with the running web and normally idle but capable of movement by engagement with the running web; means to bring the periphery of the replenishing roll into contact with the running web to thereby deflect the latter into engagement with the backing member so as to effect a pasted joint between the two webs; and means to rotate 10 the replenishing roll through its core-engaging means.

3. Web supply means including: a support having an active web roll the web of which is threaded into a machine that unwinds the web
15 from the roll; a support having core-engaging means for a rotatable replenishing web roll the web of which is to be united to the running web; a backing member normally out of contact with the running web and normally idle but capable
20 of movement by engagement with the running web; means to bring the periphery of the replenishing roll into contact with the running web to thereby deflect the latter into engagement with the backing member so as to effect a pasted
25 joint between the two webs; and additional means, other than the running web and backing member, to rotate the replenishing roll when the active web is deflected into engagement with the backing member.

30 4. Web supply means including: a support having an active web roll the web of which is threaded into a machine that unwinds the web from the roll; a support having core-engaging means for a rotatable replenishing web roll the
35 web of which is to be united to the running web; a backing member normally out of contact with the running web and normally idle but capable of movement by engagement with the running web; means to bring the periphery of the replenishing roll into contact with the running web to thereby deflect the latter into engagement with the backing member so as to effect a pasted joint between the two webs; and additional means, other than the running web and backing
40 member, to rotate the replenishing roll, said means controlled by the movement of the replenishing roll toward the active web.

5. Web supply means including: a support having an active web roll the web of which is threaded into a machine that unwinds the web from the roll; a support having core-engaging means for a rotatable replenishing web roll the web of which is to be united to the running web; a backing member normally out of contact with the running web and normally idle but capable of movement by engagement with the running web; means to bring the periphery of the replenishing roll into contact with the running web to thereby deflect the latter into engagement with the backing member so as to effect a pasted joint between the two webs; and means to rotate the replenishing roll through its core-engaging means when the active web is deflected into engagement with the backing member.

65 6. Web supply means including: a support having an active web roll the web of which is threaded into a machine that unwinds the web from the roll; a support having core-engaging means for a rotatable replenishing web roll the web of which is to be united to the running web; a backing member normally out of contact with the running web and normally idle but capable of movement by engagement with the running web; means to bring the periphery of the replenishing roll into contact with the running web

to thereby deflect the latter into engagement with the backing member so as to effect a pasted joint between the two webs; and means, controlled by the movement of the replenishing roll toward the active web, to rotate the replenishing roll through its core-engaging means. 5

7. Web supply means including: a rotatable reel to support a plurality of rotatable web rolls having core-engaging means, each of which rolls is alternately an active roll with its running web threaded into a machine and a replenishing roll the web of which is to be united to the running web of an active roll; a backing member normally out of contact with the running web and normally idle but capable of movement by engagement with the running web; means to turn the reel to bring the periphery of the replenishing roll into contact with the running web to thereby deflect the latter into engagement with the backing member so as to effect a pasted joint between the two webs; and additional means, other than the running web and backing member, to rotate the replenishing roll.

8. Web supply means including: a rotatable reel to support a plurality of rotatable web rolls 25 having core-engaging means, each of which rolls is alternately an active roll with its running web threaded into a machine and a replenishing roll the web of which is to be united to the running web of an active roll; a backing member 30 normally out of contact with the running web and normally idle but capable of movement by engagement with the running web; means to turn the reel to bring the periphery of the replenishing roll into contact with the running web to 35 thereby deflect the latter into engagement with the backing member so as to effect a pasted joint between the two webs; and means to rotate the replenishing roll through its core-engaging means. 40

9. Web supply means including: a rotatable reel to support a plurality of rotatable web rolls having core-engaging means, each of which rolls is alternately an active roll with its running web threaded into a machine and a replenishing roll 45 the web of which is to be united to the running web of an active roll; a backing member normally out of contact with the running web and normally idle but capable of movement by engagement with the running web; means to turn 50 the reel to bring the periphery of the replenishing roll into contact with the running web to thereby deflect the latter into engagement with the backing member so as to effect a pasted joint between the two webs; and additional 55 means, other than the running web and backing member, to rotate the replenishing roll when the active web is deflected into engagement with the backing member.

10. Web supply means including: a rotatable reel to support a plurality of rotatable web rolls having core-engaging means, each of which rolls is alternately an active roll with its running web threaded into a machine and a replenishing roll the web of which is to be united to the running web of an active roll; a backing member normally out of contact with the running web and normally idle but capable of movement by engagement with the running web; means to turn the reel to bring the periphery of the replenishing roll into contact with the running web to thereby deflect the latter into engagement with the backing member so as to effect a pasted joint between the two webs; and additional means, other than the running web and backing member, 75

to rotate the replenishing roll, said means controlled by the movement of the reel to bring the replenishing roll into engagement with the active web.

5 11. Web supply means including: a rotatable reel to support a plurality of rotatable web rolls having core-engaging means, each of which rolls is alternately an active roll with its running web threaded into a machine and a replenishing roll 10 the web of which is to be united to the running web of an active roll; a backing member normally out of contact with the running web and normally idle but capable of movement by engagement with the running web; means to turn 15 the reel to bring the periphery of the replenishing roll into contact with the running web to thereby deflect the latter into engagement with the backing member so as to effect a pasted joint between the two webs, and means to rotate 20 the replenishing roll through its core-engaging means when the active web is deflected into engagement with the backing member.

25 12. Web supply means including: a rotatable reel to support a plurality of rotatable web rolls having core-engaging means, each of which rolls is alternately an active roll with its running web threaded into a machine and a replenishing roll 20 the web of which is to be united to the running web of an active roll; a backing member normally 25 out of contact with the running web and normally idle but capable of movement by engagement with the running web; means to turn the reel to bring the periphery of the replenishing roll into contact with the running web to thereby deflect the latter into engagement with the backing member so as to effect a pasted joint between the two webs; and means, controlled by rotation of the reel to bring the replenishing roll toward the active web, to rotate 40 the replenishing roll through its core-engaging means.

30 13. Web supply means including: a support having an active web roll the web of which is threaded into a machine that unwinds the web 45 from the roll; a support having core-engaging means for a rotatable replenishing web roll the web of which is to be united to the running web; means to bring the periphery of the replenishing web roll into engagement with the running web 50 to thereby initiate rotation of the replenishing roll; normally inactive actuating means, other than the running web, to drive said replenishing roll; and a control device for the actuating means, controlled by initial rotation of the replenishing roll, to render the actuating means active to drive the replenishing roll.

55 14. Web supply means including: a support having an active web roll the web of which is threaded into a machine that unwinds the web 60 from the roll; a support having core-engaging means for a rotatable replenishing web roll the web of which is to be united to the running web; means to bring the periphery of the replenishing web roll into engagement with the running web to thereby initiate rotation of the replenishing roll; normally inactive actuating means, other than the running web, to drive said replenishing roll; and a control device for the actuating means, controlled by initial rotation of the replenishing roll, to render the actuating means active to drive the replenishing roll.

65 15. In a web supply means: a rotatable reel; a plurality of sets of rotatable core-engaging means for a plurality of web rolls; normally 70 inactive actuating means other than the running

web to drive each web roll one at a time; and a control device for the actuating means controlled by rotation of the reel and by initial rotation of the roll to be driven to render the actuating means active to drive the web roll.

75 16. In a web supply means: a rotatable reel; a plurality of sets of rotatable core-engaging means for a plurality of web rolls; normally inactive actuating means other than the running web to drive each web roll one at a time through the core-engaging means; and a control device for the actuating means controlled by rotation of the reel and by initial rotation of the roll to be driven to render the actuating means active to drive the web roll.

15 17. Web supply means including: a rotatable reel to support a plurality of rotatable web rolls having core-engaging means, each of which rolls is alternately an active roll with its running web threaded into a machine and a replenishing roll 20 the web of which is to be united to the running web of an active roll; normally inactive actuating means, other than the running web, to drive each web roll one at a time; and a control device for the actuating means controlled by rotation of the reel and by initial rotation of the roll to be driven to render the actuating means active to drive the web roll.

25 18. Web supply means including: a rotatable reel to support a plurality of rotatable web rolls 30 having core-engaging means, each of which rolls is alternately an active roll with its running web threaded into a machine and a replenishing roll the web of which is to be united to the running web of an active roll; normally inactive actuating 35 means, other than the running web, to drive each web roll one at a time through the core-engaging means; and a control device for the actuating means controlled by rotation of the reel and by initial rotation of the roll to be driven 40 to render the actuating means active to drive the web roll.

45 19. Web supply means including: a support having an active web roll the web of which is threaded into a machine that unwinds the web 45 from the roll; a support having core-engaging means for a rotatable replenishing web roll the web of which is to be united to the running web; a backing member normally out of contact with the running web and normally idle but capable 50 of movement by engagement with the running web; means to bring the periphery of the replenishing roll into contact with the running web to thereby deflect the latter into engagement with the backing member so as to effect a pasted 55 joint between the two webs; and means, controlled by rotation of the replenishing roll, to rotate the replenishing roll.

60 20. Web supply means including: a rotatable reel to support a plurality of rotatable web rolls 60 having core-engaging means, each of which rolls is alternately an active roll with its running web threaded into a machine and a replenishing roll the web of which is to be united to the running web of an active roll; a backing member normally 65 out of contact with the running web and normally idle but capable of movement by engagement with the running web; means to turn the reel to bring the periphery of the replenishing roll into contact with the running web to thereby deflect the latter into engagement with the backing member so as to effect a pasted joint between the two webs; and means, controlled by rotation of the reel and by rotation of the replenishing roll, 70 to rotate the replenishing roll.

21. Web supply means including: a support having an active web roll the web of which is threaded into a machine that unwinds the web from the roll; a support having core-engaging means for a rotatable replenishing web roll the web of which is to be united to the running web; a motor to rotate the replenishing roll through its core-engaging means; a backing member normally out of contact with the running web; and means to move the periphery of the replenishing roll into contact with the running web to deflect the latter into engagement with the backing member to effect a pasted joint between the two webs and to decrease the load on the motor that rotates the replenishing roll without subjecting the running web to undue strain.

22. Web supply means including: a support having an active web roll the web of which is threaded into a machine that unwinds the web from the roll; a support having core-engaging means for a rotatable replenishing web roll the web of which is to be united to the running web; variable brake mechanism that controls the speed of rotation of the active roll; a controller governed by the tension of the running web of the active roll to vary the effectiveness of the brake mechanism; a motor to rotate the replenishing roll through its core-engaging means; a backing member normally out of contact with the running web; and means to move the periphery of the replenishing roll into contact with the running web to deflect the latter into engagement with the backing member to effect a pasted joint between the two webs and to decrease the load on the motor that rotates the replenishing roll without subjecting the running web to undue strain to thereby avoid excessive movement of the controller and brake mechanism.

23. In a web supply means: a rotatable reel; a plurality of sets of rotatable core-engaging means for a plurality of web rolls; a plurality of

electric motors, one for each web roll, to drive said web rolls one at a time; and means, controlled by rotation of the reel and by rotation of the roll to be driven, to energize the motor of that replenishing roll which is to be driven.

24. In a web supply means: a rotatable reel; a plurality of sets of rotatable core-engaging means for a plurality of web rolls; a plurality of electric motors, one for each web roll, to drive said web rolls one at a time through the core-engaging means; and means, controlled by rotation of the reel and by rotation of the roll to be driven, to energize the motor of that replenishing roll which is to be driven.

25. Web supply means including: a rotatable reel to support a plurality of rotatable web rolls having core-engaging means, each of which rolls is alternatively an active roll with its running web threaded into a machine and a replenishing roll the web of which is to be united to the running web of an active roll; a plurality of electric motors, one for each web roll, to drive said web rolls one at a time; and means, controlled by rotation of the reel and by rotation of the roll to be driven, to energize the motor of that replenishing roll which is to be driven.

26. Web supply means including: a rotatable reel to support a plurality of rotatable web rolls having core-engaging means, each of which rolls is alternatively an active roll with its running web threaded into a machine and a replenishing roll the web of which is to be united to the running web of an active roll; a plurality of electric motors, one for each web roll, to drive said web rolls one at a time through the core-engaging means; and means, controlled by rotation of the reel and by rotation of the roll to be driven, to energize the motor of that replenishing roll which is to be driven.
